Dudley W. Moor, Jr., Toledo, Ohio, assignor to American
Mat Corporation, Toledo, Ohio, a corporation of Delaware

Application December 5, 1955, Serial No. 39,164

Term of patent 14 years

(Cl. D9—6)

FIG. 1.

FIG. 4

Fig. 1 is a view in perspective of a floor mat showing my new design;

Fig. 2 is a fragmentary plan view of the lower left hand corner of a floor mat as shown in Fig. 1;

Fig. 3 is a fragmentary view in perspective on a further enlarged scale, of the lower left hand corner of the fragment of the mat shown in Fig. 2; and

Fig. 4 is a fragmentary, vertical, sectional view on a further enlarged scale, taken along the line 4-4 of Fig. 3.

The area delineated by the broken lines in Fig. 2 constitutes a repeat pattern extending throughout the mat.

I claim:

The ornamental design for a floor mat, as shown and described.
